UNITED STATES PATENT OFFICE.

OSCAR WIEDERHOLD, OF JERSEY CITY, NEW JERSEY.

MEANS FOR PROTECTING AND APPLYING INCANDESCENT MANTLES.

No. 841,204.

Specification of Letters Patent.

Patented Jan. 15, 1907.

Application filed March 3, 1906. Serial No. 303,941.

To all whom it may concern:

Be it known that I, OSCAR WIEDERHOLD, a citizen of the United States, and a resident of Jersey City, Hudson county, New Jersey, have invented certain new and useful Improvements in Means for Protecting and Applying Incandescent Mantles, of which the following is a specification.

My invention relates to means for protecting and applying incandescent mantles such as are used for lighting purposes, and particularly mantles to be used in connection with inverted burners.

The object of my invention is to provide a construction including a receptacle which will not only protect the mantle efficiently during storage or shipment, but will also serve as a convenient means for properly applying the mantle to a burner.

The invention will be fully described hereinafter and the features of novelty pointed out in the appended claims.

Reference is to be had to the accompanying drawings, in which—

Figure 1 is an elevation with parts in section, illustrating the use of the receptacle in the act of applying the mantle to a burner; and Fig. 2 is a vertical section through the receptacle, the mantle being removed therefrom.

In Fig. 1 I have shown the tapering lower part A of a mixing-chamber or regenerative chamber, which receives a supply of gas and air and delivers such gas-and-air mixture to the burner-tip A', formed with an external spiral rib A². This spiral rib is adapted to be engaged by an internal spiral flange B' upon a mantle-holder which has outwardly-projecting arms B² for manipulating the mantle-holder, and downwardly-projecting arms B³, upon which the edge of the inverted mantle C is secured by means of a cord D, the edge thus being spaced from the burner and also from the body or ring B at the upper portion of the mantle-holder. These features of the burner and of the mantle-holder form the subject-matter of other applications filed by me in the United States Patent Office and are not claimed herein. It will be understood that the mantle-holder and the mantle are permanently connected with each other, and heretofore the mantle was applied by holding the outwardly-projecting arms B² between the fingers, and thus screwing the holder upon the burner-tip. This operation is objectionable in practice, not

only because the proper centering of the mantle-holder may be missed, but chiefly for the reason that it exposes the mantle to contact with the hand, and therefore to injury. To overcome these difficulties, I have provided the special receptacle or box which in combination with the mantle-holder and mantle forms the subject-matter of my present application. The said box comprises an outer shell E, the internal diameter of which at the top is such as to correspond to that of the holder at its widest portion—that is, at the arms B². The ends of these arms should frictionally engage the inner surface of the shell E. A shoulder is formed on the inside of the shell for the arms B² to rest on, and the simplest way of forming such a shoulder consists in slipping loosely into the shell a lining F, which is shorter than the portion of the shell above the bottom G. Of course, if desired, the lining F may be glued or otherwise secured to the shell; but I find that such fastening is unnecessary. The bottom G, I prefer to arrange, not at the lower edge of the shell E, but at some distance therefrom, so as to stiffen the said shell at the point where it receives the pressure of the hand when grasped, as shown in Fig. 1. The bottom may be provided with a flange G', lining the lower portion of the shell E. A cover H is fitted on the upper portion of the shell.

During storage and shipment the upper ends of the arms B² engage the inner surface of the shell E, the shoulder formed by the upper end of the lining F preventing the holder from being pushed in so far as to bring the mantle C in contact with the bottom G. The mantle C is therefore freely suspended out of contact with any part of the box. When it is desired to apply the mantle to the burner, the lid or cover H is removed, and the open end of the receptacle is brought over the burner-tip A' so as to engage the spiral flange B' with the spiral thread or rib A² of the burner. Then by turning the box or receptacle in the proper direction the flange B' is worked along the thread A² until it comes to a stop against the lower end of the chamber A. The friction between the outer ends of the arms B² and the inner surface of the receptacle is sufficient to prevent the mantle-holder from turning relatively to the box while the mantle-holder is being screwed on. After the mantle-holder has been screwed home the box can be separated from the mantle-holder by a longitudinal pull,

assisted, if necessary, by a turning movement in the same direction as in screwing the mantle-holder on.

As illustrated, the mantle is applied in an inverted position. I desire it to be understood, however, that it may be preferable to apply the mantle in an upright position—that is, with the opening of the receptacle facing downward—in which case it will of course be necessary to place the burner in a position in which it will face upward and to invert the burner only after the mantle has been screwed on.

Various modifications may be made without departing from the nature of my invention as defined in the claims. The inner lining F may be omitted from the shell, although I prefer to employ some stop which will limit the inward movement of the arms B², so as to absolutely prevent contact of the mantle C with the bottom G of the box.

What I claim as new, and desire to secure by Letters Patent, is—

1. The combination, with a mantle-holder having outwardly-projecting arms and a mantle secured to said holder, of a receptacle comprising a shell, the inner surface of which is adapted to be frictionally engaged by the outer ends of said arms, a bottom arranged

within the shell at a distance from the lower edge thereof, an inner lining arranged within the shell to within a distance of its upper edge, so as to form a stop limiting the inward movement of said arms, and a cover for the upper end of the shell. 30

2. The combination, with the mantle and a holder extending outwardly beyond the largest diameter of the mantle, of a receptacle comprising a shell, the inner surface of which is adapted to be frictionally engaged by the outer portion of the holder, and a stop arranged within said shell to limit the inward movement of the holder. 35

3. The combination, with a mantle and a holder to which said mantle is secured, said holder having a portion projecting outwardly beyond the largest diameter of the mantle, of a receptacle adapted to contain said mantle and holder, and having its inner surface of such diameter as to frictionally engage the outer portion of the mantle-holder. 40

In testimony whereof I have hereunto signed my name in the presence of two subscribing witnesses.

OSCAR WIEDERHOLD.
